UNITED STATES PATENT OFFICE

PRESTON E. GILLING, OF HADDON HEIGHTS, NEW JERSEY, ASSIGNOR TO RADIO CONDENSER COMPANY, OF CAMDEN, NEW JERSEY

ELECTRICAL CONDENSER

Application filed January 15, 1929. Serial No. 332,698.

This invention relates to improvements in a variable condenser which is especially adapted for use in connection with radio receiving sets.

In such sets it has become customary to use a plurality of condensers mounted on the same frame-work and having the rotor systems mounted on the same shaft and operated by a common dial. Where condensers are so associated, it is impossible, due to mechanical inaccuracies in manufacture, to have each condenser exactly alike; and besides, the circuits in which the condensers are used, vary in electrical characteristics, so that if the condensers were exactly alike outside of the set, they might not tune their respective circuits to the maximum point on the resonance curve when installed in the set. Certain types of compensating devices have been suggested for use in connection with a gang condenser whereby each condenser unit may be adjusted so as to get maximum efficiency in its circuit.

It is the object of my invention to provide an electrically compensating device for the purpose of securing a maximum tuning effect of each of the condensers of the gang. Another object of my invention is to provide a predetermined minimum capacity of the condenser. While attaining the principal object of my invention, another object is to provide an arrangement which is simple and cheap to manufacture and easy to assemble and adjust.

My invention will be best understood by reference to the annexed drawing, wherein:

Figure 1 is a plan view of one type of condenser to which I have applied my invention.

Figure 2 is a sectional view on the line 2—2 of Figure 1.

Figure 3 is a view of a similar section of a modified form of compensating device.

In the drawing, 1 and 2 are end plates preferable of metal, having lugs 3 turned inwardly for the purpose of supporting insulating bars 4 and 5 which are fastened to the lugs 3

by means of screws 6. The end plates 1 and 2 carry a rotor shaft 7 on which are mounted two groups of rotor plates 8 and 9, the outer peripheries of which are fastened together by tie plates 10. The stator plates of each unit are mounted on tie bars 11 which are fastened to the insulating bars 4 and 5 in any satisfactory manner as by screws 12.

While two condenser units are shown mounted in tandem, it is to be understood that any desired number of units may be so mounted and the rotors operated by the shaft 7. The present form of compensating device which is mounted between the two groups of stator plates, comprises two arcuately formed metal pieces 13 and 14. The member 13 is fastened to the two tie bars 11 of condenser 15 in any satisfactory manner as by soldered joints 17. The member 14 is fastened to the opposite tie bars of the condenser 16 in a similar manner.

In the space between the members 13 and 14, is a metallic member 18 which is carried between the insulating bars 5 and 6 by means of screws 19. The member 18 is connected to the rotor shaft 7 by means of a flexible conductor 20, as is further shown in Figure 1. The holes 21 in the bars 5 and 6 for the screws 19, are preferably made somewhat larger than the threaded part of the screws 19, so that when one or both of the screws 19 are loosened, the member 18 can be moved laterally toward or away from either of the members 13 and 14, thereby changing the capacity relation between these members. It will be observed that the members 13, 14, and 18 comprise a very small air condenser, and by shifting the relation of these parts, the capacity of the condensers 15 and 16 may be slightly altered.

If desired, the screw holes in the member 18 may be slightly off-center, as indicated by the dotted line 22, so that the member 18 may be rotated slightly as well as moved laterally.

with respect to the arcuately-formed members 13 and 14.

In Figure 3, the member 18 may be a double-pea shape, or any other shape desired, so that the capacity relationship may be varied at different angular positions of the member 18 which may be moved laterally as in Figure 2, if desired.

This arrangement provides a very simple and inexpensive compensating device for the purpose described, and while the type of condenser to which my improvement is applied is like that described in my application Serial No. 331,144, filed January 8, 1929, it is to be understood of course that the shape of the stator and rotary plates, and their method of mounting in the frame, may be varied over wide limits, without affecting the nature of my improvement.

Having thus described my invention, what I claim is:

1. In combination with a plurality of main radio tuning condensers mounted within the same frame-work and having a single control for the rotors of said condensers, a compensating condenser positioned between two of the main condensers and extending parallel to the plane of the stator plates thereof, said compensating condenser comprising; two arcuately formed members extending between the stator supports and connected one each to adjacent stator groups, and a middle member carried between said two arcuately-formed members and electrically connected to the rotor system.

2. In combination with a plurality of main radio tuning condensers mounted within the same frame-work and having a single control for the rotors of said condensers, a compensating condenser positioned between two of the main condensers and extending parallel to the plane of the stator plates thereof, said compensating condenser comprising; two arcuately formed members extending between the stator supports and connected one each to adjacent stator groups, a middle member carried between said two arcuately-formed members and electrically connected to the rotor system, and means for adjusting said middle member with respect to said two members.

3. In combination with a plurality of main radio tuning condensers mounted within the same frame-work and having a single control for the rotors of said condensers, a compensating condenser positioned between two of the main condensers and extending parallel to the plane of the stator plates thereof, said compensating condenser comprising; two arcuately formed metallic members electrically connected one each to opposite sides of adjacent stators, and a middle metallic member adjustably supported at both ends between said two arcuately-formed members and electrically connected to the rotor system,

4. In combination with a plurality of main radio tuning condensers mounted within the same frame-work and having a single control for the rotors of said condensers, a compensating condenser positioned between two of the main condensers and extending parallel to the plane of the stator plates thereof, said compensating condenser comprising; two arcuately formed metallic members electrically connected one each to opposite sides of adjacent stators, and a middle metallic member supported at both ends between said two arcuately-formed members and electrically connected to the rotor system, said middle member being mounted so it can be rotated or moved laterally with respect to said two members.

5. In combination with a plurality of main radio tuning condensers mounted within the same frame-work and having a single control for the rotors of said condensers, a compensating condenser positioned between two of the main condensers and extending parallel to the plane of the stator plates thereof, said compensating condenser comprising; two arcuately formed metallic members electrically connected one each to opposite sides of adjacent stators, and a middle metallic member supported at both ends between said two arcuately-formed members and electrically connected to the rotor system, said middle member having a form such as to change on rotation thereof its capacity relationship with said two members.

6. In a gang tuning condenser having metallic end supports fastened together by suitable frame members, a plurality of stator groups comprising parts of main condensers carried by said frame members but insulated from each other, movable plates carried between said end support members for cooperation with said stationary plates, means for slightly altering the capacity of the main condensers consisting of a small auxiliary condenser mounted between two of the frame members and extending the full width of the stator groups and between two of said groups, said auxiliary condenser comprising three parts: two arcuately-formed members electrically connected one each to adjacent stators, and a middle adjustable part electrically connected to the rotor system.

7. In a gang tuning condenser having metallic end supports fastened together by suitable frame members, a plurality of stator groups comprising parts of main condensers carried by said frame members but insulated from each other, movable plates carried between said end support members for cooperation with said stationary plates, means for slightly altering the capacity of the main condensers consisting of a small auxiliary condenser mounted between two of the frame members and extending the full width of the stator groups and between two of said groups,

said auxiliary condenser comprising three metallic parts; two arcuately-formed and electrically connected one each at opposite ends to adjacent stators, and a middle part carried between the same frame members that carry the stators, said middle part being formed and mounted so as to be either rotatably and/or laterally moved to slightly alter the capacity of the main condensers on either side of the auxiliary condenser.

10 In testimony whereof, I affix my signature.

PRESTON E. GILLING.
